AUTOMATIC SORTING MACHINE FOR GERMANIUM DIODES OR SIMILAR ARTICLE

Yoshio Otake, Mitaka, Tokyo, Japan, assignor to Tokyo Seimitsu Kogu Kabushiki Kaisha, Tokyo, Japan, a corporation of Japan

Filed Oct. 2, 1959, Ser. No. 57,770

Term of patent 14 years

(Cl. D26—5)

FIG. 1

FIG. 2

FIG. 3

FIG. 4

FIG. 5

FIG. 6

FIG. 7

FIG. 8

FIG. 9

FIG. 10

Fig. 1 is a front elevational view of an automatic sorting machine for germanium diodes or similar articles showing my new design;

Fig. 2 is a right side elevational view;

Fig. 3 is a rear elevational view;

Fig. 4 is a left side elevational view;

Fig. 5 is a top plan view;

Fig. 6 is a bottom plan view thereof;

Fig. 7 is a front elevation view, on an enlarged scale of one panel of the machine of Figs. 1-6;

Fig. 8 is a front elevation view on an enlarged scale, of another panel of the machine of Figs. 1-6;

Fig. 9 is a perspective view, on an enlarged scale, of the machine taken from in front of and to the right of the machine; and

Fig. 10 is a perspective view, on an enlarged scale, taken from in front of and to the left of the machine.

I claim:

The ornamental design for an automatic sorting machine for germanium diodes or similar article, substantially as shown.
